(57) **CLAIM**

The ornamental design for a compact mirror pill container as shown and described.

DESCRIPTION

FIG. 1 is a top front perspective view of a compact mirror pill container showing the claimed design according to an embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom rear perspective view thereof; and,

FIG. 9 is a top front perspective view thereof in an open position.

1 Claim, 9 Drawing Sheets
